UNITED STATES PATENT OFFICE.

EMMANUEL HUTTER, OF RIVE DE GIER, FRANCE.

MACHINE FOR GRINDING GLASSWARE.

SPECIFICATION forming part of Letters Patent No. 239,170, dated March 22, 1881.

Application filed October 13, 1880. (No model.)

To all whom it may concern:

Be it known that I, EMMANUEL HUTTER, of Rive de Gier, France, have invented a new and Improved Machine for Grinding Glassware, of which the following is a specification.

The object of my invention is to provide a new and improved machine for grinding glassware, such as tumblers, goblets, and similar articles, which is simple in construction and operation and can conveniently be adjusted and regulated to suit the various forms and sizes of the articles and the grinding-stones.

In the accompanying drawings, Figure 1 is a cross-sectional elevation of my improved machine for grinding glassware. Fig. 2 is a side elevation of the circular table carrying the articles to be ground. Fig. 3 is a side elevation of the eccentric and frame for rotating the carrying-disk or grinding-table. Fig. 4 is a horizontal cross-sectional view on the line xx , Fig. 1, of my improved machine for grinding glassware. Fig. 5 is a horizontal cross-sectional view of the same on the line yy , Fig. 1. Fig. 6 is a view of the under side of the frame carrying the grinding-stone. Fig. 7 is a plan view of the device for holding the articles in place. Fig. 8 is a cross-sectional elevation of the same on the line zz , Fig. 7. Fig. 9 is a horizontal section through letters xx of Fig. 1, to show the squared shaft.

Similar letters of reference indicate corresponding parts.

The grinding-stone A is mounted on a shaft, B , journaled in the ends of a fork, C , attached to the lower end of a tube, D , preferably of steel, journaled vertically at the ends of the arms E of a post or standard, F , and provided with a belt-pulley, G .

A semi-spherical or bell-shaped vessel, J , is attached to the lower end of a tube, K , preferably of steel, passing through the tube D . This tube K is not to rotate, and for this reason its upper end is squared, and is connected by a squared sleeve, a , with a squared tube, L , guided by an arm, M , of the standard F . The lower edge of the bell J is toothed, and a pinion, N , mounted on the end of the shaft B , engages with this pinion; or the edge of the bell and the wheel N may be arranged to act upon each other by friction. The tube L , and consequently the tube K also, is suspended from the end of a rod, O , provided with a screw-thread at the end, which takes in the inner thread of a sleeve, P , provided with a

cog-wheel, H . The opposite end of the sleeve P is threaded inversely, and a rod, Q , provided with a corresponding screw-thread, takes in it. This rod Q is guided at b , and by means of a connecting-rod, R , is connected with one end of a lever or beam, S , pivoted on the standard F at T , and provided with an adjustable counter-weight, U , at the other end, near which a rod, V , is suspended from the beam S .

A ring, A' , surrounding an eccentric disk, B' , is attached to the lower end of the rod V , so that the end, c , of the beam S can be raised or lowered by rotating the shaft C' of the eccentric B' by means of the crank D' or like device. A cam, E' , is also mounted on the shaft C' , and is surrounded by a frame, F' , connected with a rod, G' , which is also connected with a sprung-pawl, H' , engaging with a ratchet-wheel, J' , mounted on a vertical shaft, K' , journaled in the plate L' , supported by the legs ff .

A circular or annular plate, M' , is mounted on the upper end of the shaft K' , and is provided on the under side with projections g , that glide in an annular groove, h , in the upper side of the plate L' . The plate M' is provided with an annular strip, N' , of rubber, leather, or analogous material, upon which strip the articles O' that are to be ground rest, so as to have a soft and yielding bearing. To hold the articles a series of rings, P' , provided with adjustable springs Q' , having a strip, k , of rubber or leather at the end, are attached to a series of arms, R' , pivoted radially at their inner ends to the plate M' , whereas the outer ends are locked to the outer edge of the plate M' . The articles are placed into the rings P' , and are held yieldingly by the springs Q' . The water, that must be poured upon the articles during the grinding, is conducted to each article O' by a flexible tube, and flows off through the apertures l of the plate M' into the annular gutter S' of the plate L' .

The distance from the end d of the beam S to the bottom point of the grinding-stone A must be regulated according to the sizes of the stone A or the articles O' . For this purpose the cog-wheel H is arranged to engage with a barrel-pinion, T' , having a beveled cog-wheel, m , at its lower end, and is journaled vertically in a bracket, U' , projecting from the standard F . A beveled cog-wheel, n , on the horizontal shaft o engages with the wheel m ,

and a cog-wheel, *p*, at the other end of this shaft *o* engages with the cog-wheel *r* of a vertical shaft, *s*, provided with a hand-wheel, *V'*, at the lower end.

5 There are to be as many teeth in the ratchet-wheel *J'* of the shaft *K'* as there are holding-rings *P'* on the plate *M'*.

As the tube *D* rests upon the top of the bell *J*, which is rigidly attached to the tube or rod *K*, it is evident that the tube *D* will rise and descend with the tube *K*.

The operation is as follows: The articles to be ground are placed upon the disk or plate *M'*, and are held in their proper position by the rings *P'*. The rods *O* and *Q* are then adjusted according to the size of the article *O'* or the stone *A* by turning the hand-wheel *V'*, for thereby the barrel-pinion *T'* is rotated, and as the cog-wheel *H* engages with this barrel-pinion *T'* in all its positions, this wheel *H* and the sleeve *P* attached thereto will also be rotated; but as the two ends of sleeve *P* are threaded inversely the rods *O* and *Q* will be separated if the wheel *V'* is rotated in one direction, and will be drawn together if rotated in the opposite direction. The weight *U* is then adjusted on the beam *S*, according to the weight suspended from the end *d* of the same, so as to balance it. By rotating the crank *D'*

30 a very short distance from left to right the end *e* of the beam *S* will rise and the end *d* descend, and the stone *A* will come in contact with the article *O'* to be ground; but at the same time that the above movements take place the cam *E'* pushes the frame *F'* and the rod *G'* in the direction of the arrow *a'*, and the spring-pawl *H'* rotates the shaft *K'* the distance of one tooth of the wheel *J'*, and the plate *M'* is rotated the distance occupied by an article, *O'*, so that by the oscillating movement of the crank the stone *A* is raised and the pawl *H'* is drawn back, and then the pawl is pushed forward, the disk *M'* rotated, and the stone *A* lowered. The tube *D'* is rotated by means of

45 the belt *W* passing around the pulley *G*. As the bell *J* is rigid and the pinion *N* that engages with the teeth of the bell is rotated on the vertical axis by the fork *O*, it follows that the pinion must also rotate on its horizontal axis—that is, it rotates on its shaft *B*, and at the same time runs around in a circle parallel to this axis; but as the stone *A* is mounted on the shaft *B*, it will rotate with this shaft, but at the same time it will rotate on a diametrical vertical axis, as it is mounted in the middle of the shaft *B*, mounted in the fork *O*, which is rotated in the vertical axis.

The stone *A* may be replaced by others of different size or structure, according to the hardness, nature, or size of the glass article that is to be ground.

Having thus described my invention, what I claim as new, and desire to secure by Letters Patent, is—

65 1. A machine for grinding glassware, made substantially as herein shown and described, and consisting of a grinding-stone mounted on

a shaft pivoted in the ends of a revolving fork and provided with a pinion engaging with the lower edge of a fixed bell within the fork, which bell and fork are suspended from an adjustable rod attached to the end of a pivoted beam, by means of which the stone may be raised from or lowered upon the article to be ground, as may be required.

2. In a machine for grinding glassware, the combination, with the suspended rotating grinding-stone *A*, of an adjustable suspension device, of the pivoted beam *S*, the connecting-rod *V*, the eccentric *B'*, and the shaft *C'*, substantially as herein shown and described, and for the purpose of raising the stone *A* by means of a slight rotation of the shaft *C'*, as set forth.

3. In a machine for grinding glass, the combination, with the suspending-rods *Q* and *O*, having inverse screw-threads at the ends, of the sleeve *P*, threaded inversely at the ends, the cog-wheel *H*, the barrel-pinion *T'*, and a train of gearing and shafting for rotating the barrel-pinion *T'* at will, substantially as herein shown and described, and for the purpose of adjusting the length of the suspending device of the grinding-stone according to the size of this stone or the size of the article to be ground.

4. In a machine for grinding glassware, the combination, with the plate *M'*, of a series of radially-pivoted holding-rings *P'*, provided with cushioned springs *Q'*, substantially as herein shown and described, and for the purpose of holding the articles securely.

5. In a machine for grinding glassware, the combination, with the plate *M'*, having pivoted holders *P'* for the articles to be ground, of the shaft *K'*, the ratchet-wheel *J'*, having as many teeth as there are holders *P'* on the plate *M'*, and of the spring-pawl *H'*, substantially as herein shown and described, and for the purpose of rotating the plate *M'* a like distance every time.

6. In a machine for grinding glassware, the combination, with the shaft *C'*, the eccentric *B'*, and the frame *F'* of the rod *G'*, the pawl *H'*, the ratchet-wheel *J'*, the shaft *K'*, the plate *M'*, the connecting-rod *V*, the pivoted beam *S*, and the grinding apparatus suspended from the same, as set forth, for the purpose of passing the articles to be ground under the stone and lowering the stone upon the article by a slight rotation of the shaft *C'*.

7. In a machine for grinding glassware, a rotating grinding-stone, an adjustable suspension-rod, a pivoted beam to which the suspension-rod is attached, a rod for raising or lowering the ends of the beam, an eccentric for operating this rod, a revolving table for holding the articles to be ground, and a pawl connected with the shaft of the eccentric for rotating the table, all these parts in combination, as set forth.
